UNITED STATES PATENT OFFICE

154,680

DESIGN FOR A GARDEN TOOL

Albert Roy Hines, Columbus, Ga.

Application October 25, 1946, Serial No. 134,241

Term of patent 3½ years

(Cl. D35—2)

To all whom it may concern:

Be it known that I, Albert Roy Hines, a citizen of the United States of America, residing at Columbus, in the county of Muscogee and State of Georgia, have invented a new, original, and ornamental Design for a Garden Tool, of which the following is a specification, reference being had to the accompanying drawing, forming a part thereof.

In the drawing:

Figure 1 is a side elevational view of a garden tool embodying my new design,

Figure 2 is a side elevational view of the same at right angles to Figure 1,

Figure 3 is a top plan view of the same.

The dominant features of my design are shown in full lines in the drawing.

I claim:

The ornamental design for a garden tool, as shown and described.

ALBERT ROY HINES.
